(57) **CLAIM**

I claim the ornamental design for a ski binding, as shown and described.

DESCRIPTION

FIG. 1 is a top, front, and left-side perspective view of a ski binding according to an embodiment of the present invention. FIG. 2 is a left-side elevation of the embodiment of FIG. 1; the right side is a mirror image thereof.

FIG. 3 is a front elevation of the embodiment of FIG. 1.

FIG. 4 is a rear elevation of the embodiment of FIG. 1.

FIG. 5 is a top plan of the embodiment of FIG. 1; and,

FIG. 6 is a bottom plan of the embodiment of FIG. 1.

The broken lines shown in the drawings are for illustrative purposes only and form no part of the claimed design.
